T. P. CAIN

HOUSING FOR TAPPET AND ROCKER ARMS FOR INTERNAL COMBUSTION ENGINES

Filed May 2, 1923

FIG. 1

FIG. 2

FIG. 3

FIG. 5

FIG. 4

INVENTOR.

Thomas P. Cain

BY

U. G. Charles

ATTORNEY.

UNITED STATES PATENT OFFICE.

THOMAS P. CAIN, OF WICHITA, KANSAS.

HOUSING FOR TAPPET AND ROCKER ARMS FOR INTERNAL-COMBUSTION ENGINES.

Application filed May 2, 1923. Serial No. 636,123.

To all whom it may concern:

Be it known that I, THOMAS P. CAIN, a citizen of the United States, residing at Wichita, in the county of Sedgwick and State of Kansas, have invented certain new and useful Improvements in Housings for Tappet and Rocker Arms for Internal-Combustion Engines, reference being had to the accompanying drawings, which form a part of this application.

My invention relates to housings for exposed operating parts of internal combustion engines.

The objects of my invention are as follows:

First. To provide a housing that will encase the moving mechanisms that are exposed on the engines, sheltering it from dust or other exposure.

Second. A housing that tends to muffle the noise of the engine.

Third. A housing that supports and holds in place a fabric oiling device.

Fourth. A housing made of two parts and simple to apply.

Referring to the drawings;

Fig. 1 is a top view of the housing.

Fig. 2 is a side elevation showing the cap and side housing assembled.

Fig. 3 is an end view of Fig. 2.

Fig. 4 is a sectional view through the block and housing taken on line A—A in Fig. 5, looking in the direction of the arrows.

Fig. 5 is a sectional view of the housing, showing its relative position on the engine.

1 is the cap covering the top of the engine in which is interposed a fabric sheet 2, said sheet being saturated with oil tends to lubricate the trunnions of rocker arm 3, said cap resting with one edge on the engine at 4 and on the opposite side resting on the housing 5 at B, said housing 5 has its bearing on the block 6 and is firmly attached to

the block by means of a bolt 7, engaging a plate D on the opposite side thereof, said plate engaging with the walls of the cylinders at E, enclosing the openings between said cylinders, and being spaced from said block by means of a boss 8, and when tension is produced by tightening the bolt 7, the said housing 5 is held firmly to the block, the cap 1 is attached firmly in position by means of bolt 9, said bolt screwing into the rocker arm bracket at 10, functioning as binding means to hold the rocker arm rod

11, firmly in place when the usual set screw that is used for that purpose is removed for convenience of attaching said bolt 9. The said bolt 9 has a nut 12 by which means proper tension is imposed, holding said cap firmly in place. Oil holes 13 are drilled in through the top of cap 1 for convenience of injecting oil to the fabric sheet 2, said sheet being held in its proper position by means of holes through which bolt 9 will pass as shown at C in Fig. 5. That portion of the housing marked 5 is made to conform to the contour 9 of the block by means of a shoulder 14 and in said housing are openings to accommodate for the adjusting rod for distributor 15, said rod passing through the elongated slot 16, and at 17 is a hexagon opening through which passes the exhaust connection 18 by the application of my improved housing, the tappet 19, and rocker arms 20, and connecting rod 21 are protected from the dust which is so freely discharged through the radiator by action of the fan and by this protection the said operative parts are kept in a clean condition, free from grit, preventing the bearings from wearing and failing to function as they should, and by supplying oil continuously on the fabric sheet to the pivot joints, eliminating the possibility of overlooking oiling of said joints as must be done the ordinary way, by the use of the oiling can, lubricating each joint separately, and the said sheet fitting closely to the side walls of cap 1, functions as a dust proof means for the rocker arm and all moving parts connected thereto should the dust pass through the oiling apertures 13.

Such modifications may be employed as lies within the scope of the appended claims.

Having thus described my invention, what I claim as new and desire to secure by Letters Patent is;

In a housing for tappets and rocker arms for internal combustion engines, a housing having its edges fitting closely to the outside walls of the engine, said housing comprising two parts namely a cap and side wall, said cap having apertures functioning as oil holes, apertures in alignment with rocker bearings, bolts connected to said bearings and extending through last said apertures and having nuts screwed thereon as binding means, the edges of said cap adapted to rest on the engine and on the side wall, a fabric sheet interposed within

said cap and fitting closely to the side walls thereof, said fabric sheet being saturated with oil, said oil being poured through first said aperture, said oil saturated fabric sheet 5 functions as dust proof means for the rocker arms of said engine, a side wall engaging and covering that side of the engine on which the rocker arm connecting rods are positioned, bosses on said side walls 10 engaging with the walls of the cylinders as

spacing means, an opening in said side wall to receive the exhaust pipe connection, an opening through which will pass the distributor adjusting rod, an anchor bolt and plate to bind said side wall firmly to the walls of 15 the engine, said adapted to close the space between the two intermediate cylinders of the engine completing the housing.

THOMAS P. CAIN.
